CLAIMThe ornamental design for a tray with magnetic back panel,
as shown and described.**DESCRIPTION**FIG. 1 is a back perspective view of a tray with magnetic
back panel showing the new design;

FIG. 2 is a front perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines are for the purpose of illustrating portions
of the tray with magnetic back panel, and form no part of the
claimed design.**1 Claim, 5 Drawing Sheets***Fig. 1*
